BUILDING

Austin T. Levy, Harrisville, R. I.

Application July 10, 1936, Serial No. 89,959

36 Claims. (Cl. 72—1)

This invention relates to buildings of the type described in my Patent No. 2,104,869, issued January 11, 1938.

In the said patent, I have described a prefabricated building in which panels of story height are set in apertures formed by a sill member, channeled wall studs and an upper plate member, said panels comprising boards of suitable thermal and sound insulating material having applied to their faces upright reenforcing rods which serve also as means for spacing from the board, anchoring sheets for coating material. These anchoring sheets serve as a means for effectively anchoring an outer coat of stucco or the like, and an inner 10 coat of plaster, applied after erection of the wall. The reenforcing rods also serve as means for positioning the panels with respect to the sill member and the plate member.

One of the objects of my present invention is 20 to furnish provisions in a building of this general type for mounting the frames for closures such as windows and doors.

Another object is to provide improved door and window frame mounting means applicable to a 25 construction system such as disclosed in my patent and by means of which window and door frames can be mounted in a panel type wall of the character above indicated in a convenient and rapid manner and at small expense.

30 The invention also purposed the provision of a panel-like unit of simple form in which a closure frame is incorporated and which can be readily shipped to the building site and readily handled and quickly assembled with the other parts of the 35 building. This unit, although of story height as preferably made, is of relatively light weight and comprises in addition to the frame for the window or other closure, a panel element comprising an insulating board having applied thereto satisfactory means for anchoring coating material to be applied after erection, and also means for reenforcing the board element and positioning it with respect to the structural elements such as the sill member and plate member.

45 A further object which I have in view is to provide a portable closure frame carrying unit or element, which involves in addition to the closure frame and an associated coating anchoring structure, one or more wall studs having provisions 50 for positioning one or more adjacent panels forming a part or parts of a wall structure. The wall referred to may be an outer wall or, in the case where the frame is a door frame, it may be an inner wall or partition.

55 These and other objects of my invention will,

however, appear more clearly hereinafter or be manifest to those skilled in the art.

In the accompanying drawings:

Figure 1 is a side elevation of a portion of a building constructed in accordance with my invention, showing a panel unit comprising a metal window frame and a metal casement window, portions of the structure being broken away;

Fig. 2 is a vertical sectional view of the structure shown in Fig. 1;

Fig. 3 is a fragmentary elevation on an enlarged scale of the window carrying panel shown in Fig. 1, with the coating anchoring sheet and the coating partly omitted;

Figs. 4, 5, 6 and 7 are respectively sections on lines 4—4, 5—5, 6—6, and 7—7 of Fig. 3;

Fig. 8 is a detail vertical section showing the means for positioning the lower edge portion of the panel;

Fig. 9 is a detail perspective view partly in section, showing portions of the completed wall and the metal window frame and window;

Fig. 10 is a broken view, partly in elevation and partly in section, showing a modified form of my invention in which a wooden window frame and window of the sliding sash type are employed;

Figs. 11, 12, 13 and 14 are respectively sections on lines 11—11, 12—12, 13—13 and 14—14 of Fig. 10;

Fig. 15 is a view showing the upper portion of a further modified type of wall unit which in this case has provisions for mounting a door such as a front door;

Fig. 15^A shows the lower portion of the unit;

Fig. 16 is a vertical sectional view of the unit;

Fig. 17 is a section on line 17—17 of Fig. 15^A, and

Fig. 18 is a section on line 18—18 of Fig. 15^A.

In Figs. 1 and 2, I have shown a portion of a building having a concrete foundation A supporting an outer wall B comprising panels of story height positioned at their lower ends by a sill or lower plate C and at their upper ends by an upper plate member D, above which are located sloping roof rafters E. The wall B comprises panels B' which are only fragmentarily shown and which are preferably of the kind disclosed in my patent above mentioned. Between these panels is interposed a window carrying panel element or unit B² constructed in accordance with my present invention.

In the form shown in Figures 1 to 9 inclusive, the window carrying panel unit is provided with a metal window of the casement type, generally indicated at F, and it comprises panel board por-

10

40

45

50

55

tions surrounding the window frame, and further comprises channeled stud members G at the sides of the unit which are attached to the window frame.

Each of the stud members G is composed of channel members 20, 21 arranged back to back and suitably interconnected as by welding. The outer channel member 21 of the unit receives the edge of the adjacent panel B'. To the inner channel members 20 of the unit the frame of window F is connected by means hereinafter described. The panel board portion of the unit above the window is indicated at 22, the panel board portion below the window at 23, and the portions at the sides of the window at 24. The studs G are adapted to be fastened to the sill member C by suitable means such as angle clips 25 and 26. In the structure shown in Figs. 1 to 9, the sill member is of angular cross section, having a horizontal plate portion 27 resting on the upper surface of the foundation, and an upstanding flange portion 28. The angle clips 25 are connected to the studs and to the portion 27, and the angle clips 26 are connected to the studs and to the flange or upstanding portion 28. At their upper ends the studs G are provided with plates or pads 29 which may be connected thereto as by welding. Extending across the stud members and resting on the plates or pads 29 is an upper plate member 30 which may, as herein shown, be a thin ribbon-like member. Other forms of sill members and plate members may be used if desired.

In the form illustrated, the window frame is supported from the stud members **G** by transverse supports, there being one such support adjacent the head of the window and another adjacent the sill thereof. The upper or head support, as illustrated, comprises a channel member **31** and a member **32**. The channel member **31** is received at its respective ends within the opposing channels of the marginal stud members and is suitably attached to the channel members **20** as by spot welding, as indicated at **33**. At its intermediate portion, where the same lies alongside the head portion **34** of the window frame, the member **32** is of angular cross section, having a portion **35** attached to the channel member **31**, a depending portion **36**, and a flange portion **37** connected to the head portion of the window frame as by bolts **37a**. The end portions of member **32** are suitably attached to the channel members **20** as by spot welding, as indicated at **38**.

53 A board 40 of compressed wood fiber or other insulating material is received at its side edges in channels 20 and at its lower edge portion in the channel of channel member 31. Against the outer surfaces of the board 40 are placed upright reenforcing rods 41, the upper extremities of which are adapted to project through perforations in the plate member 30 for locating the unit relatively to said plate member. The rods 41 serve to space from the board, coating anchoring sheets 42 at the inner and outer faces of the panel. These coating anchoring sheets are applied to the rods and connected to the board by means such as wire fastener loops 42a passing through perforations in the board and so arranged as to hold opposite rods in place relatively to the board and to hold the anchoring sheets to the rods. The lower extremities of the rods pass through perforations in fugs 39 bent down from the side walls of channel member 31.

At the inner side of the building wall the coating anchoring sheet 42 is continued downwardly.

past the rods into adjacency to the head portion of the window frame, while at the outer side of the wall the coating anchoring sheet supported by the outer rods is directed horizontally into adjacency to portion 36 of the angular window-frame supporting member. 5

Between the sides of the window frame and the stud members of the unit are interposed panel boards 43. The upper edges of these boards are adjacent the bottom of channel member 31. The outer side edges of these boards are received within the channel members 20 of the studs. At their inner edges, these boards 43 are connected to the window frame by means of metal members 44 of angular cross section, projecting laterally from the window frame, as shown in Figs. 6 and 7. Each of these members 44 has intermediate its edges a V-shaped portion 45 connected to the edge of the corresponding board 43 by means such as nails 46. At the inner side of the wall, the portion 45 is integrally united to a portion 47 connected as by bolts 48 to the side portion 49 of the window frame. Member 44, throughout its length, fills the space between the side of the window frame and the inner edge of panel board portion 43. The portion 47 is continued to form a flange 50 occupying a laterally projecting position with respect to the side portion of the window frame and underlying the portion of the inner coating anchoring sheet 42 which is adjacent the side of the window frame. It will be understood that the coating anchoring sheets 42, if made of sufficient length to extend throughout the height of the panel unit, are cut away to provide openings in which the window frame is received, or that, if desired, each sheet covering the board portions respectively above, below and at the sides of the window frame, may be made of sections appropriately joined together in a manner understood by those skilled in the art.

Figs. 6 and 7 show the relation of the coating anchoring sheet portions **42b**, **42c** at the side of the window frame to the window frame, and to the board portion **43** and the stud member **G**. From these views, it will be noted that the anchoring sheet portion **42b**, which overlies the flange portion **50**, previously described, is in spaced relation to the board **43** and extends laterally in spaced relation to the inner stud face beyond the center line of the stud to a line adjacent the outer margin of the stud so as to overlap a portion of the anchoring sheet **42d** of an adjacent panel **B'**. Also, it will be noted that at the outer side of the wall the sheet portion **42c** extends over a flange portion **51** integral with member **44** and is continued in spaced relation to board portion **43** past the center line of the stud to overlap a coating anchoring sheet **42e** forming a part of the adjacent panel **B'**.

For securing the lower or sill portion of the window frame to the stud members G of the window carrying unit, a cross member 54 is employed. This member may be a metal member of angular cross section having a web 55, an upwardly directed flange 56 and a downwardly directed flange 57. The flange 57 may be located within the channel member 20 of the stud and suitably attached to said channel member as by spot welding, as indicated at 58. The end portion of the flange portion 56 may also be received within the channel member 20 and attached thereto as by spot welding, as indicated at 59. In this particular case, the sill member of the window frame is of hollow sectional metal construction and the member 54 is suitably attached 75

to the sill member as by welding it thereto. The hollow sill portion at the inner face of the wall is indicated at 60 and the hollow sill portion at the outer face of the wall at 61.

5 Between the cross member 54 and the sill member C is a panel board portion 62 having its side edges received in the stud channels 29 and having its upper edge in close proximity to the sill of the window frame and behind flange 57 of member 54. Adjacent opposite faces of board 62 are reenforcing rods 63, similar to the rods 41 previously described. The upper extremities of the rods 63 at the outer face of the wall are received and held within sockets 64 in sill section 61. The upper extremities of the rods at the inner face of the wall extend through perforations in a plate 64' welded to the web 55 of the cross member 54. The upper extremities of these rods also extend upwardly through perforations in the 10 sill section 60 and are housed in said section. Coating anchoring sheet portions 42f are disposed over the rods 63, as in the structure at the upper part of the unit. These sheet portions 42f and their associated rods and panel board portion 15 are interconnected by suitable fasteners 42a such as previously described. The rods 63 at their lower end portions extend downwardly through perforations 65 in the sill member so that the lower edge of the panel is firmly positioned relatively to the sill member. If desired, the lower extremities of the rods 63 may enter sockets 63a formed in the foundation below the sill member.

For the purpose of preventing dislocation of 20 panel board portion 62 relatively to the unit before the unit is assembled, the portion 62 may be attached to member 54 by means such as pins 66 or the like, and if desired, the uppermost board portion 40 may be fastened to member 31 by means such as pins 67.

It will be understood that the anchoring sheet portions associated with the uppermost and lowermost panel board portions extend laterally beyond the edges of the board portions to overlap 25 sheets of adjacent panels in the same manner as described in connection with the anchoring sheet portions of the side board portions 43 and substantially as shown in Figs. 6 and 7.

The structure above described and comprising 30 the two studs, the window frame, and the panel board structure surrounding the window frame, is made in unitary form before shipment to the building site, and it will be apparent that by the provisions described the unit may be readily 35 placed in assembled relation to the sill member of the building. The adjacent panels B' may be readily assembled, the boards of said panels being received at their side edges in the outer channels of studs G. The studs G may then be 40 fastened in their final position, and at the appropriate time the upper plate will be placed in position and interlocked with the upper reenforcing rods and connected as by welding to the pads of the stud members. After erection, an 45 outer coating of cementitious material 52 such as stucco is applied to the outer anchoring sheet so as to cover the panel board and the studs and the exposed portion of the sill member. At the inner face of the wall, a coating 53 of plaster is 50 applied. These coatings are very firmly anchored by the coating anchoring sheets located as above described. The coatings may be very readily applied in those locations which are immediately adjacent the window frame and will 55 be strongly held in those places as well as in the

locations where the coatings overlie the panel boards and the studs.

As shipped, the unit usually does not contain a window sash, the latter being placed in its frame at a later stage.

5 In the form of my invention shown in Figures 10 to 14, inclusive, a wooden window frame and a wooden window of the sliding sash type are employed. In this form the transverse members supporting the window frame from the studs are omitted and the studs do not form parts of the unit, but, on the other hand, are independent units positioned individually with respect to the sill member and the upper plate. In panels of this type, the board portions directly support the 10 frame in an opening provided therefor. The window frame can be built into a full length panel board cut out to provide an opening to receive the parts of the window frame or, if desired, the board can be made in sections which are placed 15 around the frame and interconnected. In the form shown herein, it may be assumed that a full length insulating board 68 is provided with a rectangular opening and that window frame 69 is built into the board so that it will be firmly positioned with respect to the margins of the opening. The frame 69 comprises the usual head 70, the jambs 71 and the window sill member 72, all made 20 of wood and having the usual trim, and the frame is equipped with the usual sliding sash 73.

25 The head 70 is provided at its upper part with a longitudinal groove in which is received a metal channel 74 receiving the lower edge of the board portion above the opening. This channel member 74 has associated therewith bent down lugs 75, 30 having perforations receiving the lower ends of upright reenforcing rods 76 positioned against the opposite faces of the board and carrying the coating anchoring sheets 77 which are fastened to the rods and to the board by the fastener loops 78. 35 The channel member 74 is attached to member 70 by means such as screws 79. The fastener loops 78 hold the rods and anchoring sheets in fixed relation to the board and unit. Attached to the window sill member 72 is a channel member 80 similar 40 to member 74 but in inverted position, and this channel member is set over the lower edge of the window frame opening. Associated with the lower portion of the board beneath the window frame are reenforcing rods 81 having the same relation 45 to the coating anchoring sheets 77 as the rods 76 previously described and similarly held in place relatively to the panel unit. The side walls of the channel member 80 are bent down at intervals to provide perforated lugs 80a similar to lugs 75 receiving the upper ends of the rods 81.

50 In this form of my invention, as shown herein, the sill member of the wall is constituted by a channel member 82 resting on and suitably secured to the upper face of the foundation wall. 60 The rods 81 have their lower ends flush with the lower edge of the board, and the channel member 82 is of such width as to receive the lower edge of the board with its associated rods within the groove of the channel, the outer portions of the 65 rods being in substantial contact with the channel side walls. Thus, the panel is properly positioned with respect to the sill. The studs 83 extend into the channel of the sill and are fastened to the sill in any suitable manner.

70 In this form of my invention, as herein shown, the portions 71a of the coating anchoring sheets 77 which are disposed at the sides of the window frame have their inner edges disposed in close proximity to the jamb members 71, as shown in 75

Figure 12. The outer edge portions of said anchoring sheet portions extend laterally beyond the outer edges of panel board portions 84 at the sides of the window frame opening. These panel board portions 84 are positioned relatively to the window frame by having their inner edges 85, which define parts of the window frame opening, extend into grooves 86 in the outer faces of the jamb members 71. The trim and the sash are applied 10 to the window frame in the usual manner and they need not be described in detail. After the panel has been placed in assembled relation to studs 83 and adjacent ordinary panels B', the outer and inner plastic coats 87 and 88 are applied 15 to the panel faces as in the structure previously described.

In Figures 15, 15A, 16, 17 and 18, I have shown a panel carrying a wooden frame for a door such as an outside door. In this form, the structure is 20 similar to that described in connection with Figures 1 to 9, inclusive, in that studs which form parts of the unit are interconnected by a transverse upper member. The method of mounting the reinforcing rods at their ends which are adjacent 25 the frame is, however, similar to that described in connection with Figs. 10 to 14, inclusive. In this last modification, the studs G are interconnected by an upper transverse member or head 89 in the form of a channel, above which is 30 positioned a panel board section 90 having associated therewith reinforcing rods 91 and coating anchoring sheets 92. Connected to the header 89 and extending downwardly therefrom are channeled bucks 93 connected near their lower ends 35 to and supporting a transverse member 94 having its ends connected to the bucks. The ends of the channel member 89 are connected to channels 20 of studs G in a suitable manner as by being spot welded therein. The end of the channel 89 is of 40 such width as to fit into the channel 20. The ends of the transverse member 94 are fastened as by welding to the backs of the channeled bucks.

The wooden door frame has a head 95 located 45 immediately below member 89 and provided with sockets 96 receiving the lower extremities of the rods 91. The jamb members 97 of the door frame are disposed inside of and immediately adjacent the bucks 93, lying against the back portions thereof. A sill member 98 of the door frame rests 50 at its lower edge on the member 94 and its lower surface is provided with sockets 99 receiving the upper ends of the rods 100, which pass through perforations in bent down lugs 101 associated with the side walls of channel member 94. The rods 55 100 are associated with a lower board section 102 whose upper edge is received in channel member 94 and whose side edges are adjacent the bucks. Board sections 103 at the sides of the panel are received in the opposing channels provided by the 60 bucks 93 and the adjacent stud members. As in the form shown in Figs. 1 to 9, suitable means such as pins may be employed for preventing dislocation of the panel board portions from the unit. As before, coating anchoring sheets are applied 65 to opposite faces of the panels, and these cover the board portions and extend over the studs in the manner previously described. These sheets also extend over the sides of the bucks 93 and over one or more sides of channels 89 and 94. 70 In this form of my invention, as in the other forms shown herein, a channel member placed adjacent a member of the closure frame receives the edge of a panel board portion and also positions the rod members, and the anchoring material 75 spaced from the board by the rod members is

extended over the channel member into adjacency to the frame to assist in anchoring the coating.

The studs G extend down into the channeled sill member 82 and are fastened therein by means such as bolts 105. The bucks 93 also extend 5 down into the channel of the sill member and each is fastened to said member by means such as a bolt 106. At the joint, spacers 107 are interposed between the side walls of the sill member and the outer faces of the buck, as shown in Figure 18. 10 Similar spacers are interposed between the side walls of the sill and the outer faces of the stud and are associated with the connection comprising the bolts 105.

It will be noted that in all forms of my invention 15 herein described, the panel comprises a closure frame surrounded by panel board portions, all of said portions having coating anchoring sheet material associated therewith, and the portions of the board above and below the frame having 20 associated therewith, in addition to the anchoring material, rods which space said material from the board and also serve in positioning the panel or unit relatively to its supporting structure. The lower ends of the lower rods assist in positioning 25 the panel relatively to the sill, and the upper ends of the upper rods assist in positioning the panel relatively to the plate member. The rods so space the anchoring sheets from the board (including those portions of the sheets at the sides 30 of the closure frame) that the coatings can be very effectively anchored. In all forms herein shown, the wall panel is formed as a unit comprising a board portion having an opening therein, a closure frame mounted in said opening, 35 reinforcing rods applied to the board portion, and a coating anchoring sheet spaced from the board portion by the rods and extending around the closure frame.

My invention provides a prefabricated panel 40 unit of light weight having desirable insulating properties and which can be manufactured inexpensively and readily handled, and which includes in its structure a closure frame strongly supported and around which the coating material can be 45 readily applied and strongly anchored. The improved panels are also provided with means for strongly reinforcing the panel board associated with the closure frame so that the panel offers high resistance to buckling. By my invention, 50 a panel is provided by means of which a window or door frame can be included in a prefabricated structure which is conveniently and rapidly assembled. These and other advantages of my improved structure will be apparent to those 55 skilled in the art.

While I have in this application described several embodiments of my improved panel, it will be understood that these are illustrative only, and that numerous other modifications may be 60 made and various structural details changed without departing from the principles of my invention as appearing herein, or from the scope of the claims. For example, it is not necessary in all aspects of the invention that the space below the 65 closure frame be filled by a panel member or board portion, nor is it necessary in all aspects of the invention that panel members or board portions be provided between the sides of the closure frame and the side edges of the wall unit or panel. 70

What I claim as new and desire to secure by Letters Patent is:

1. A prefabricated wall unit for buildings comprising spaced studs, a panel having an aperture therein and also opposite edges positioned by said 75

studs, and a closure frame in said aperture and carried by said studs and also positioning said panel.

2. A prefabricated wall unit for buildings comprising spaced studs, a panel having opposite edges positioned by said studs and comprising a plurality of panel boards enclosing an aperture in said panel, and a closure frame in said aperture carried by said studs and also positioning the edges of the boards which define said aperture.

3. A prefabricated wall unit for buildings comprising a board portion having an aperture therein, a closure frame mounted in said aperture, and coating anchoring sheet material spacing means applied to the face of said board portion above and below said frame.

4. A prefabricated wall unit for buildings comprising panel means having an aperture therein, studs positioning opposite edges of said panel means, a closure frame mounted in said aperture and carried by said studs, and anchoring material spacing means carried by said panel means and said frame.

5. In a building, the combination of plate and sill members and spaced stud members connecting the same at spaced points to form a side wall opening, and prefabricated panel means having portions located between said studs and having their lateral edges positioned by said studs, re-enforcing means carried by the face of said panel means, and coating anchoring sheet material applied to the face of said panel means and spaced therefrom by said re-enforcing means.

6. In a building, the combination of plate and sill members and a pair of stud members connecting the same at spaced points to form a side wall opening, and prefabricated panel boards located between said studs one above the other and having their lateral edges positioned by said studs, re-enforcing rod means carried by the faces of said boards which lie adjacent said sill and plate members, and coating anchoring sheet material applied to the faces of all said boards and spaced apart therefrom by said re-enforcing rod means on the upper and lower boards.

7. In a building, the combination of plate and sill members and vertical studs connecting the same at spaced points to form a side wall panel opening, a transverse member extending across said opening and sub-dividing the same, and prefabricated panel portions positioned by said studs and transverse member at their vertical and horizontal edges respectively, said panel portions comprising insulating boards having coating anchoring sheet material thereon spaced from the face of said board.

8. In a building, the combination of plate and sill members and vertical studs of channel cross section connecting the same at spaced points to form a side wall panel opening, transverse members extending across said opening and sub-dividing the same, and prefabricated panel portions comprising insulating boards having their vertical edges received within the channels of said studs and their horizontal edges positioned by said transverse members, and coating anchoring sheet material extending over the face of said panel portions and spaced from the faces of said boards.

9. In a building, the combination of plate and sill members and vertical studs comprising spaced confronting channels connecting said plate and sill members and forming a wall opening of story height, and a plurality of superposed panel portions having their vertical edges positioned within the channels of said studs, coating anchoring

sheet material covering said superposed panel portions, and reenforcing rod means secured to the face of certain of said panel portions spacing said sheet material therefrom.

10. In a building, the combination of plate and sill members and studs connecting the same at spaced points to form a side wall opening, spaced members connecting said studs intermediate the ends of the latter, a prefabricated panel comprising board portions having their edges positioned by said studs and intermediate members, and re-enforcing rod means carried on the face of said panel and extending from marginal edges thereof into adjacency to said intermediate members.

11. In a building, the combination of plate and sill members and studs connecting the same at spaced points to form a side wall opening, vertically spaced transverse members connecting said studs intermediate the ends of the latter, and panel means above and below said transverse members having their edges positioned by said studs and transverse members.

12. In a building, a prefabricated wall portion for supporting a plurality of panels comprising a framework including marginal channel frame members and inner channel frame members connecting opposite marginal frame members and, in conjunction with said marginal frame members, forming a prefabricated, unitary frame having a plurality of panel openings, and panel members forming closures for said openings and having their edges received within the channels of said framework.

13. A prefabricated wall unit for buildings comprising a panel board portion having an aperture therein, a closure frame mounted in said aperture in spaced relation to a marginal edge thereof, and reenforcing means for said marginal edge adjacent and extending along said edge.

14. A prefabricated wall unit for buildings comprising a panel board portion having an aperture therein, a closure frame mounted in said aperture in spaced relation to a marginal edge thereof, anchoring material spacing means disposed along said marginal edge, and coating anchoring material spaced thereby from the opposite faces of said board portion along said edge.

15. A wall panel for buildings comprising a board portion of story height having an aperture therein, a closure frame mounted in said aperture, rods applied to the face of the board portion above and below said aperture, and coating anchoring sheet material spaced from the board portion by said rods and extending about said frame.

16. In a building, a sill member, an upper plate member, and wall stud members, said members defining a panel space, a panel in said space having an aperture therein, a closure frame mounted in said aperture, and reenforcing rods carried by the panel above and below the aperture respectively, the rods at the lower portion of the panel cooperating with said sill member and the rods at the upper portion cooperating with said plate member in positioning the panel in said space.

17. In a building, a sill member, an upper plate member and wall stud members, said members defining a panel space, a panel in said space having an aperture therein, a closure frame mounted in said aperture, and reenforcing rods carried by the panel above and below the aperture respectively, the rods at the lower portion of the panel cooperating with said sill member and the rods at the upper portion cooperating with said plate member in positioning the panel in said

space, and coating anchoring sheet material outside of said rods and having portions extending over the studs and other portions extending into close proximity to the closure frame.

5 18. A prefabricated wall panel for buildings comprising a closure frame having head, jamb and sill members, panel board portions disposed above and below said frame, and substantially vertical rods for spacing coating anchoring material from 10 the board portions, certain of said rods being disposed above the head member of the frame and others below the sill member thereof.

15 19. A prefabricated wall panel for buildings comprising a closure frame having head, sill and jamb members, channel members adjacent the head and sill members respectively, and board portions engaged in said channel members and extending upwardly and downwardly respectively from said frame, each board portion having coating anchoring material spaced from the face thereof and extending over one of said channel members.

20 20. A prefabricated wall unit comprising a panel and a channel element at one side margin thereof receiving an edge of said panel and adapted to act as a stud member in positioning said unit in a wall.

25 21. A prefabricated wall unit comprising a panel and elements having channels receiving therein the respective side margins of said panel, said elements forming parts of the unit and adapted to act as stud members in positioning said unit in a wall.

30 22. A prefabricated wall unit comprising a panel and elements for positioning said panel at the respective side margins thereof forming parts of the unit and having exterior channels adapted to receive therein the side marginal portions of adjacent panels.

35 40 23. A wall unit comprising a panel, marginal channel elements receiving and positioning the side margins thereof forming parts of the unit and adapted to act as stud members, and a closure frame within said panel connected to and carried by said marginal elements.

45 45 24. A prefabricated wall unit for buildings comprising spaced double-channel uprights adapted to act as stud members, a closure frame between and connected to said uprights, and panel means between said uprights having lateral edges engaged in opposing channels of said uprights.

50 55 25. A prefabricated wall unit for buildings comprising spaced uprights adapted to act as stud members, a closure frame between and connected to said uprights and of less width than the space between said uprights, panel means at the sides of said frame between the same and the uprights having their remote edges positioned by said uprights, and panel means extending across the space between the uprights above said frame also having their side edges positioned by said uprights.

55 60 65 70 26. A wall unit for buildings comprising uprights of story height having inwardly directed channels, transverse members between the uprights intermediate of the ends of the latter, supported by said uprights, a closure frame between said transverse members and spaced laterally from said uprights, panel members above and below said frame, and panel members between said uprights and the sides of said frame, said panel members having their edges contiguous to said uprights received in the channels of the latter.

75 27. A prefabricated wall unit for buildings comprising spaced uprights having confronting chan-

nels, transverse members between the uprights intermediate of the ends of the latter, a closure frame between said transverse members, and panel means between said uprights having lateral edges engaged in the channels of said uprights. 5

28. A prefabricated wall unit for buildings comprising spaced uprights, upper and lower transverse members between said uprights, a closure frame between the transverse members, panel members between the uprights above and below 10 said transverse members, and upright reenforcing rods applied to faces of said panel members, certain of said rods extending to the upper edge of the unit and others to the lower edge thereof, said first named rods having their lower ends engaging the upper transverse member and said second named rods having their upper ends engaging the lower transverse member. 15

29. A prefabricated wall unit for buildings comprising spaced uprights, an upper transverse member interconnecting said uprights at points below their upper ends, bucks extending downwardly from said transverse member, a lower transverse member interconnecting said bucks, a closure frame between said bucks, and between said transverse members, a panel member extending between the uprights above said frame, and side panel members between the bucks and the uprights. 20 25

30. The combination with a wall frame having 30 a sill member and a plate member, of a prefabricated wall panel having spaced uprights extending between and connected to said sill member and plate member, a transverse member interconnecting said uprights, bucks extending 35 downwardly from said transverse member and connected at their lower ends to the sill member, a transverse member interconnecting said bucks, and a closure frame mounted between said transverse members and between said bucks. 40

31. A prefabricated panel unit for building walls comprising board means having an opening therein, a closure frame supported by said board means in said opening and including head and sill members, upright rods applied to said board means in groups respectively located above and below said closure frame, means for connecting the upper rods to the head member of said frame, and means for connecting the lower rods to the sill member of said frame. 45 50

32. In a prefabricated wall unit for buildings, a pair of upright channelled studs, transverse members interconnecting said studs intermediate of their ends, a closure frame carried by and between said transverse members and having its side edges spaced from said studs, panel members at the sides of said frame having their inner edges spaced from said frame and their outer edges received in channels of said studs, members carried by the sides of said closure frame and projecting laterally therefrom in spaces between said frame and the inner edges of said panel members, panel members between said stud members above and below said transverse members, and coating anchoring material extending over said panel members and over said laterally projecting members on the frame. 55 60 65

33. A panel unit for building walls comprising a closure frame having head and sill members, upper and lower channel members applied to said head member and said sill member respectively, board portions having inner edges engaged in said channel members and extending substantially continuously around the frame, reenforcing rods connected to a face of the board portion above 70 75

the frame and positioned by the upper channel member, and reenforcing rods connected to a face of the board portion below the frame and positioned by the lower channel member.

- 5 34. A panel unit for building walls comprising a closure frame, a channel member adjacent and in fixed relation to said frame at one margin thereof, a panel member engaged in said channel member, rods applied to a face of said panel member and connected to said channel member, and coating anchoring material spaced from said panel member by said rods and extending over said channel member at the side thereof into adjacency to said closure frame.
- 10 35. A prefabricated wall unit for buildings comprising spaced upright stud members, vertically spaced transverse members connecting said stud members, panels between said stud members presenting a closure aperture and including

panel boards extending from said stud members toward said aperture, a closure frame in said aperture spaced from said boards, and coating anchoring material means bridging the spaces between said panel boards and said closure frame. 5

36. A prefabricated wall unit for buildings comprising spaced upright stud members, vertically spaced transverse members connecting said stud members, panels between said stud members presenting a closure aperture and including panel boards extending from said stud members toward said aperture, a closure frame in said aperture spaced from said boards, coating anchoring material means bridging the spaces between said panel boards and said closure frame. 10
